DESIGN FOR A BADGE

David Bruce Gibbs, New York, N. Y.

Application July 18, 1938, Serial No. 78,559

Term of patent 14 years

To all whom it may concern:

Be it known that I, David Bruce Gibbs, a citizen of the United States, residing at New York, in the county and State of New York, have invented a new, original, and ornamental Design for a Badge, of which the following is a specification, reference being had to the accompanying drawing, forming part thereof.

In the drawing:

Fig. 1 is a front elevational view of a badge, showing my new design.

Fig. 2 is an edge view thereof.

I claim:

The ornamental design for a badge, as shown.

DAVID BRUCE GIBBS.
